Edward S. Anderson Inventor
By Louis Bagley his Attorney

UNITED STATES PATENT OFFICE.

EDWARD S. ANDERSON, OF MABEL, MINNESOTA.

ROAD DRAG.

1,420,605.

Specification of Letters Patent. Patented June 20, 1922.

Application filed September 20, 1919. Serial No. 325,188.

To all whom it may concern:

Be it known that I, EDWARD S. ANDERSON, a citizen of the United States, residing at Mabel, in the county of Fillmore and State 5 of Minnesota, have invented certain new and useful Improvements in Road Drags, of which the following is a specification.

My invention relates to an improvement in road drags, and the object is to provide 10 means for simultaneously adjusting the blades or scrapers, and another object is to provide a light, simple and inexpensive machine for road construction.

With these objects in view, my invention 15 comprises a plurality of blades or scrapers, either two or three bars extending lengthwise of the machine and pins pivoted to the bars and to the blades and means for simultaneously tilting the several blades.

20 In the accompanying drawings—

Figure 1, is a plan view.

Figure 2, is a perspective view.

Fig. 3 is a fragmentary view in rear elevation of the left-hand rear end;

25 Fig. 4 is a section on line 4—4 of Fig. 3.

The numerals 1, 2 and 3, represent blades or scrapers, the blades or scrapers 1 and 3, extending parallel with each other, and the blade or scraper 2, preferably inclined in the 30 opposite direction as shown in Fig. 1 to throw dirt from one side toward the center where it is caught by blade 1.

The blades or scrapers have brackets 4, extending forwardly and arranged in pairs one 35 above the other, there being three of these preferably on the front and rear scraper blades 1 and 3 and two on the intermediate scraper of blade 2.

Rods 5 extend upwardly through these 40 brackets and are pivotally connected to the channel-bars 7 and admit of the blades turning thereon as hinges, the rods having a head 6, at the lower end and at their opposite end these rods are pivoted to the channel 45 bars 7, which extend parallel with one another longitudinally of the track and with the blades form the frame work of the grader.

At the center of the drag, rods 8 are employed. 50 These are like rods 5, but longer, and instead of having a single channel-bar pivoted to them, there are two channel-bars

17 and 18, one above the other and parallel with each other, and pivoted at their ends to the upper ends of the rods 8 by pins or rivets 55 13, as shown in Fig. 2. A hand-lever 9 is pivoted to each of these channel-bars 17 and 18 by means of pins or rivets 19, and this handle-bar carries a spring-actuated latch 10 which operates in connection with a segment 11 secured to the upper channel-bar 17. The lower end of the hand-lever terminates in a pintle corresponding to one of the rods 5 extending through a bracket 4 on the back of blade 2, and having a head 6 on its 60 lower end. By swinging the hand-lever, all three blades are simultaneously and correspondingly tilted.

A brace-rod extends from the channel-bar 18 to bar 7 and engages an opening 13' 70 therein.

The rear end of the rear scraper or blade is provided with an adjustable extension 14, pivoted thereto and provided with a spring latch 15 for holding it in different positions, 75 in that way causing the blade to scrape deeper or shallower as desired at that point according to the adjustment, the lower edge of the blade being cut away as at 16, for this purpose. By means of this adjustable extension, the soil is distributed over the wheel tracks, in order to make a firm road bed.

I claim,

A road drag including end bars in substantial parallelism, a pair of parallel blades pivotally connected to said bars, an additional pair of bars one spaced above the other in the center of the drag, rods pivoted to both of said last-mentioned bars at their ends, and connected with said blades, an additional blade located between the parallel blades and at an angle thereto, a rod pivotally connecting the last-mentioned blade to an end bar, and a rod terminating in a handle connected with said blade and pivotally 95 connected with each bar of said pair of bars, and means for holding the handle in a desired position respecting said pair of bars, the whole so arranged that oscillation of said handle about said pivots varies the angle of each of the blades simultaneously.

In testimony whereof I affix my signature.

EDWARD S. ANDERSON.
